UNITED STATES PATENT OFFICE.

OTTO CHARLES WOVRIES, OF DAYTON, OHIO, ASSIGNOR OF ONE-HALF TO
EDWARD BORDERWISCH, OF DAYTON, OHIO.

SPEED-REGULATOR FOR EXPLOSIVE-ENGINES.

SPECIFICATION forming part of Letters Patent No. 695,261, dated March 11, 1902.

Application filed January 30, 1901. Serial No. 45,322. (No model.)

To all whom it may concern:

Be it known that I, OTTO CHARLES WOVRIES, a citizen of the United States, and a resident of Dayton, in the county of Montgomery and State of Ohio, have invented certain new and useful Improvements in Explosive-Engines, of which the following is a full, clear, and exact description.

The object of the invention is to provide certain new and useful improvements in explosive-engines, whereby the explosive mixture and the exhaust are accurately controlled by a single rotary valve and the latter is automatically controlled by the governor to insure a uniform speed of the engine.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a side elevation of the improvement. Fig. 2 is an enlarged sectional plan view of the same on the line 2 2 in Fig. 1. Fig. 3 is an enlarged transverse section of the same on the line 3 3 in Fig. 1. Fig. 4 is a similar view of the same on the line 4 4 in Fig. 1. Fig. 5 is a like view of the same with parts in a different position. Fig. 6 is a sectional plan view of the valve and the governor connection for rotating the valve, and Fig. 7 is 35 an enlarged perspective view of the arm controlled by the governor.

In the cylinder A of the explosive-engine reciprocates a piston B, connected by a pitman C with a crank-arm D on the main driving-shaft E of the engine. The working chamber A' of the cylinder A is connected by a channel A² with a valve-chest F, in which is mounted to turn a rotary-valve F' having its stem F² extending through a suitable stuffing-box carried on the casing F. The stem F² has a connection G with a shaft H, mounted to turn in suitable bearings and carrying a bevel gear-wheel H', in mesh with a bevel gear-wheel E', secured on the main driving-shaft E, so that when the engine is running normally the bevel gear-wheel E', mesh-

ing with the bevel gear-wheel H', imparts a half-revolution to the shaft H for every full revolution of the main driving-shaft E. The connection G is controlled by the engine-governor I, so that in case the speed increases beyond a normal rate then the connection G is actuated by the governor to temporarily disconnect the shaft H from the stem F² in order that the rotary valve F' may remain stationary for the time being—that is, until the speed of the engine is reduced. The valve F' is open toward the channel A² and is formed in its cylindrical wall with a port a, adapted to register alternately with ports b and c, formed in 65 the casing F and connected with an inlet-pipe J and an exhaust-pipe K.

On the valve F' is secured a member L of an electric igniting device, said member rotating with the valve to make and break contact with a member L', extending through the channel A² into the working chamber A'. The inner end of the member L' is secured or formed on the inner end of a shaft L², mounted to turn in suitable bearings attached to 75 the cover A³ of the cylinder, the shaft L² extending through a stuffing-box N to the outside of the cover, as is plainly indicated in Fig. 2. The outer end of the shaft L² is pressed on by a spring O, so as to hold the 80 member L' normally in the path of the member L, the member L' abutting against a stop-button L³, as indicated in Fig. 3. The members L and L' are so arranged relatively to each other and the port a that when the 85 member L makes contact with the member L' then the port a is out of register with both ports b and c.

The construction of the connection G is as follows: On the outer end of the stem F² is 90 secured a disk G', formed in its face with a recess G², adapted to be engaged by a pin G³ on an arm G⁴, fulcrumed in a casing G⁵, enclosing the disk G' and secured on the shaft H, previously mentioned. A spring G⁶ presses 95 the arm G⁴ and holds the pin G³ normally in engagement with the recess G², so that when the shaft H is rotated the arm G⁴ and its pin G³ carry the disk G' around, thus rotating the stem F² and its valve F' at the rate of one 100 revolution to two revolutions of the main shaft E. On the outer end of the arm G⁴ is

formed a bevel G^7 , adapted to be engaged by a correspondingly-shaped bevel G^8 on a lever G^9 , connected with the governor-stem I' , so that when the engine runs at more than normal speed then the governor I by its stem I' 5 imparts a swinging motion to the lever G^9 , so that the bevel G^8 moves into the path of the bevel G^7 to cause the arm G^4 to swing against the tension of its spring G^6 and to move the pin G^3 out of engagement with the recess G^2 . When this takes place, the shaft H and the stem F^2 are disconnected, and consequently the stem and valve remain stationary for the time being—that is, during the time the lever G^9 by its bevel G^8 holds the arm G^4 from dropping with the pin G^3 into the recess G^2 . As the arm G^4 rotates with the shaft H , it is evident that the bevel G^7 leaves the bevel G^8 during part of the revolution of the casing G^5 , 20 the pin G^3 then resting on the face of the disk G' while the latter is stationary, and when the shaft H and the casing G^5 have made a complete revolution and the bevel G^8 is still in the previous position then the arm G^4 is 25 again prevented from swinging its pin G^3 into engagement with the recess G^2 . It is evident that this takes place as long as the engine is running at a speed above a normal rate of speed; but as soon as the engine returns to 30 a normal rate of speed then the bevel G^8 swings out of the path of the bevel G^7 and then the arm G^4 swings to move its pin G^3 in engagement with the recess G^2 of the disk G' . When this takes place, the valve F' is again 35 rotated in unison with the shaft H . The pin G^3 , recess G^2 , and port a are so arranged relatively to each other that the port a is in register with the port c at the time the pin G^3 moves out of engagement with the recess G^2 40 by the action of the governor-lever G^9 , as previously described, so that during the time the valve F' is at a standstill its port a registers with the port c and the exhaust-pipe K , while the port b is completely cut off, (see 45 Fig. 4,) and the charge of explosive mixture cannot pass into the cylinder for the time being.

The operation is as follows: When the engine is running and the port a registers with the port b , then the explosive mixture can 50 pass from the pipe J , registering ports b and a into the valve F' , and from the latter into the working chamber of the cylinder A by way of the channel A^2 . When the desired 55 quantity of explosive mixture has passed into the working chamber A' , then the port a has moved out of register with the port b , and then the piston B during its return stroke compresses the explosive mixture, after which 60 an explosion takes place by a spark from the igniting device—that is, on the member L leaving the member L' . The explosion sends the piston B on its working stroke to impart a rotary motion to the shaft E , and during 65 the time the explosion takes place the port a is out of register with both ports b and c ; but as soon as the piston B nears the end of

its working stroke then the port a registers with the port c , and the products of combustion can now escape from the working chamber. During the return stroke of the piston the products of combustion are completely 70 expelled from the cylinder, and during the next inward stroke of the piston B the port a moves from the port c to the port b , and a new charge of explosive mixture passes into 75 the cylinder, to be compressed therein on the return stroke of the piston B . The above-described operation is then repeated.

In case the engine runs at a high rate of speed then the governor I acts on the lever G^9 and the connection G , previously described, to disconnect the shaft H from the stem F^2 , so that the valve F' remains stationary for the time being and in such position 85 that the port a registers with the exhaust-port c . When this takes place, the working chamber is connected with the atmosphere and the products of combustion pass out of the cylinder and without subsequent compression during the compression period, and the explosive mixture is completely shut off 90 from the engine until the speed is reduced to a normal rate.

Having thus fully described my invention, 95 I claim as new and desire to secure by Letters Patent—

1. An explosive-engine having a rotary valve provided with a port adapted to alternately register with an inlet-port and an exhaust-port, and having its stem provided with a disk having a recess on its face, a revoluble shaft, a pivoted and spring-pressed arm carried by the shaft and provided intermediate of its ends with a pin adapted to enter the disk of the valve-stem, and a lever for engaging the end of the said arm to operate the same, said lever being under the control of the governor, as set forth. 100

2. An explosive-engine having a rotary valve, provided with a port adapted to alternately register with an inlet-port and an exhaust-port, a driving connection for said valve, and comprising a disk on the valve-stem and formed with a recess in its face, a 110 shaft rotated from the main driving-shaft of the engine, an arm pivoted on said shaft and having intermediate of its ends a pin adapted to engage said recess, said arm also having a bevel at its end, and a lever under the control of the governor and having a bevel adapted to swing into the path of the bevel on the end of said arm, to swing the latter out of engagement with said disk by the pin of the arm leaving said recess, as set forth. 115

3. An explosive-engine having a rotary valve, provided with a port adapted to alternately register with an inlet-port and an exhaust-port, a driving connection for said valve, and comprising a disk on the valve-stem and formed with a recess in its face, a 120 shaft rotated from the main driving-shaft of the engine, an arm pivoted on said shaft and having intermediate of its ends a pin adapted to 125

to engage said recess, said arm also having a bevel at its ends, a lever under control of the governor and having a beveled end adapted to engage the bevel on said arm, to swing the latter out of engagement with said disk by the pin of the arm leaving said recess, and a spring pressing said arm, to engage the pin with the recess, on the governor-lever swinging out of the path of said arm, as set forth.

- 10 4. An explosive-engine having a rotary valve, provided with a port adapted to alternately register with an inlet-port and an exhaust-port, a driving connection for said valve, and comprising a disk on the valve-stem and formed with a recess in its face, a shaft rotated from the main driving-shaft of the engine, a pivoted and spring-pressed arm carried by said shaft and having intermediate of its ends a pin adapted to engage said recess, 20 said arm also having a bevel at its end, and a lever under the control of the governor and having at its end a bevel adapted to swing into the path of the bevel on said arm, to swing the latter out of engagement with said disk 25 by the pin of the arm leaving said recess, said pin and recess being so arranged relatively to said ports that when the pin leaves the recess the rotary-valve port is in register with the exhaust-port, as set forth.
- 30 5. In an explosive-engine, a working chamber, a valve-chest, a channel connecting the chest and chamber, a rotary valve having a port adapted to alternately register with an inlet-port and an exhaust-port, a driving mechanism for the valve, a governor controlling the driving mechanism, and an igniting device consisting of an arm on the projection of the valve, an angular and spring-pressed arm secured in the head of the cylinder and extending through the channel into the valve-chest and into the path of the arm carried by the valve, 35 40 as set forth.

6. In an explosive-engine, a working chamber, a valve-chest having inlet and exhaust ports, a rotary valve having a port adapted to alternately register with the inlet and exhaust ports, and provided at its end with a disk having a recess in its face, a revoluble shaft provided at its end with a slotted casing into which the disk of the valve-stem extends, 45 a pivoted and spring-pressed arm mounted in the casing and having its end projecting out through the slot of the same, said arm being provided intermediate of its ends with a pin adapted to enter the recess of the disk and 50 having a bevel on its projecting end, a pivoted lever having a bevel adapted to engage the bevel of the said arm, and a governor to the stem of which the said lever is pivoted, as set forth. 60

7. In an explosive-engine, a working chamber, a valve-chest having inlet and exhaust ports, a channel connecting the chest and chamber, a chambered rotary valve open toward the channel and provided with a central projection and with a port adapted to alternately register with the inlet and exhaust ports, a driving mechanism for the valve, a governor controlling the driving mechanism, and an igniting device consisting of an arm on the projection of the valve, an angular and spring-pressed arm secured in the head of the cylinder and extending through the channel into the valve-chest and into the path of the arm carried by the valve, 65 70 75 as set forth.

In testimony whereof I have signed my name to this specification in the presence of two subscribing witnesses.

OTTO CHARLES WOVRIES.
